REED

Conaway P. Beaver, Pasadena, Calif.

Application February 20, 1939, Serial No. 257,420

2 Claims. (Cl. 84—376)

This invention relates to reeds.

The general object of the invention is to provide an improved reed construction which is particularly adapted for musical instruments such as accordions.

A more specific object of the invention is to provide a reed member which is so constructed that the number of reeds employed in a musical instrument may be reduced.

Another object of the invention is to provide a novel mounting for a reed.

Other objects and the advantages of this invention will be apparent from the following description taken in connection with the accompanying drawing, wherein:

Fig. 1 is an end view of an accordion embodying the features of my invention;

Fig. 2 is an enlarged fragmentary end view of an accordion with parts broken away;

Fig. 3 is a front elevation of a reed box with parts broken away;

Fig. 4 is a section taken on line 4—4, Fig. 3;

Fig. 5 is a section taken on line 5—5, Fig. 3 on an enlarged scale;

Fig. 6 is a front elevation of a modified reed box with parts broken away;

Fig. 7 is a section taken on line 7—7, Fig. 6 on an enlarged scale;

Fig. 8 is a section taken on line 8—8, Fig. 6 on an enlarged scale;

Fig. 9 is a section taken on line 9—9, Fig. 6 on an enlarged scale;

Fig. 10 is a fragmentary section of a further modification of a reed box; and

Fig. 11 is a section taken on line 11, Fig. 10 on an enlarged scale.

Referring to the drawing by reference characters I have indicated generally at 10 an accordion in which is embodied the features of my invention. The accordion shown is of a standard type and includes the usual reed racks 12.

In Figs. 3, 4 and 5 I have indicated one of my improved reed devices generally at 13. As shown the reed device 13 includes a metal reed block 14 having a rectangular aperture 15 therethrough. At each end the block 14 includes an outwardly directed flange 16 and adjacent the lower end of the aperture includes a similar flange 17 having a notch 18 therethrough intermediate the length thereof.

The reed block 14 is adapted to support a metal reed 20 which includes a tapered vibrating tongue 21 and an enlarged base portion 22. The base 22 of the reed is positioned below the block flange 17 with the tongue extending through the

notch 18. The reed base 22 is secured to the block 14 as by a rivet 23.

Positioned in the block 14 between the upper flange 16 and the flange 17 I provide a plate 24. This plate has a thickness less than the height 5 of the flanges 16 and 17 so that the plate is free to shift. The plate has an aperture 25 therein which also opens through the lower end of the plate. The aperture 25 is tapered to match the taper of the reed tongue 21 and is slightly wider 10 and longer than the adjacent portion of the reed tongue. The plate is adapted to shift to either side of the reed with the reed in an intermediate position between the two extreme positions of the 15 plate.

On the block 14 I provide a cover 26 which includes a face plate 27 having depending flanges 28 on all four sides. The face plate 27 has a rectangular aperture 29 therein of substantially the same size as that of the aperture 15 in the 20 block 14.

The inner face of the block 14 above the flange 17 is preferably covered with a sound deadening material 30 such as a suede leather or suede paper and the inner surface of the cover face plate 25 27 is preferably covered with a similar sound deadening material 31. The reed device 13 is mounted on and hermetically sealed to the reed block 14 in the usual manner.

When air is forced through the reed block aperture in the direction indicated by the arrow A in Fig. 5 the air pressure forces the plate 24 into tight engagement with the padded face of the cover face plate 27. In this position the plate 24 is slightly spaced in one direction from the adjacent face of the reed tongue in which position the reed tongue vibrates in the plate aperture 25.

When air is forced through the cover aperture in the direction indicated by the arrow B the air pressure forces the plate 24 into tight engagement with the padded face of the block 14. In this position the plate 24 is slightly spaced in a reverse direction (from that previously mentioned) from the adjacent face of the reed tongue 45 as indicated by the broken lines in Fig. 5. Thus it will be seen that from whichever side the air pressure is directed past the reed the plate 24 shifts to a position beyond the reed so that the reed always vibrates in the plate aperture 25. 50 Thus a single reed performs the same function heretofore performed by two reeds.

In Figs. 6 to 9 I have shown a modification of my invention which is indicated generally at 35. In the modification I employ a double reed device 55

so that the reeds may be grouped in pairs. In the modification the device includes a block 36 having a pair of apertures 37 therein and having flanges 38, 39 and 40 similar to the flanges 16 and 5 17 previously described.

The block 36 supports a pair of reeds 41 which are similar to the reed 20 previously described and which are held in place by rivets 42. The flange 39 is notched as at 43 and through the 10 notches the reeds 41 extend. A plate 44 similar to the plate 24 includes a pair of apertures 45 similar to the apertures 25.

A cover 46 similar to the cover 26 previously 15 described is employed in the modification and the inner face of the block 36 above the flange 39 and the inner surface of the cover 46 are covered with sound deadening material 47 and 48 respectively.

The reed device shown in Figs. 6 to 9 is mounted 20 in the same manner as the device shown in Figs. 3 to 5 and the operation of the plate and the reed is the same.

In Figs. 10 and 11 I have indicated a reed device generally at 50. The reed device 50 is similar 25 in all respects to the reed device 13 except that the cover 26 is omitted so I have indicated like portions thereof by similarly primed reference numerals. With the device 50 a sound deadening pad 51 is placed on the face of the reed 30 rack 12 and the reed block 14 placed thereon in such a manner that the plate 24 works between the pad 51 and the pad 30'.

From the foregoing description it will be apparent 35 that I have provided a novel reed device for wind instruments which is simple in construction and highly efficient in use.

Having thus described my invention I claim:

1. For use with an accordion having a reed 40 rack therein, a reed device, said reed device including a reed block having an aperture therethrough intermediate its length, said reed block having a flange protruding from one face thereof at each end and adjacent the lower end of said aperture, said intermediate flange having a notch

therein, a cover on said block engaging said flanges and including side walls surrounding said reed block, said cover having an aperture therethrough of the same size as said block aperture, a flexible reed, said reed including a tapered 5 tongue portion and an enlarged base portion, said reed base being secured to said reed block below said intermediate flange and said reed tongue being positioned in said notch and a plate member positioned between said cover and said block, 10 said plate being of less thickness than the space between said cover and said block, said plate having an aperture therethrough from face to face and opening through the bottom, said aperture being larger than said reed tongue and 15 tapered to match the reed tongue.

2. For use with an accordion having a reed rack therein, a reed device, said reed device including a reed block having an aperture therethrough disposed intermediate its length, said reed block 20 having a flange protruding from one face thereof at each end and adjacent the lower end of said aperture, said intermediate flange having a notch therein, a cover on said block engaging said flanges and including side walls surrounding said 25 reed block, said cover having a rectangular aperture therethrough of the same size as said block aperture, a flexible metal reed, said reed including a tapered tongue portion and an enlarged base portion, said reed base being secured to 30 said reed block below said intermediate flange and said reed tongue being positioned in said notch, a plate member positioned between said cover and said block, said plate being of less thickness than the space between said cover and 35 said block, said plate having an aperture therethrough from face to face and opening through the bottom, said aperture being slightly larger than said reed tongue and tapered to match said reed tongue, the inner face of said block and said 40 cover being covered with a sound deadening material.

CONAWAY P. BEAVER.
